UNITED STATES PATENT OFFICE.

EDWARD MARSH, OF CHICAGO, ILLINOIS.

SHARPENER FOR RAZOR-BLADES.

1,316,965.

Specification of Letters Patent. Patented Sept. 23, 1919.

Application filed January 27, 1919. Serial No. 273,270.

To all whom it may concern:

Be it known that I, EDWARD MARSH, a citizen of the United States, residing at the city of Chicago, in the county of Cook and 5 State of Illinois, have invented certain new and useful Improvements in Sharpeners for Razor-Blades, of which the following is a specification.

This invention relates to improvements in 10 devices for sharpening razor blades, and it consists in certain peculiarities of the construction, novel arrangement and operation of the various parts thereof, as will be hereinafter more fully set forth and specifically claimed.

The principal object of the invention is to provide a manually held and manipulated sharpener for razor blades, particularly detachable blades, such as are used in many 20 safety razors, which shall be foldable and compact in form so as to be conveniently carried in the pocket if desired, simple and inexpensive in construction, strong, durable and efficient in operation. Another object is 25 to provide a sharpener of the above named general character, wherein the arrangement, construction and the character of the material of the parts thereof is such as to cause the sharpening sheet or member, when the 30 device is in use, to conform to the contour of the palm of the hand on which the device is mounted, to the end, that substantially a plane or a more or less curved surface of the sharpening member may be presented to 35 the blade in the operation of sharpening the same. Still another object is to provide means for detachably mounting the sharpening member on the body or supporting member of the device, in order that it may 40 be readily removed when worn or accidentally cut, and may be replaced by a new one. Other objects and advantages of the invention will be disclosed in the foregoing explanation and description.

45 In the accompanying drawing which serves to illustrate an embodiment of the invention:

Figure 1 is a perspective view showing the sharpener in operative position on one hand 50 of the user and the safety razor blade held in the other hand in about the position it will occupy in the operation of sharpening the same:

Fig. 2 is a detached rear perspective view 55 of the sharpener;

Fig. 3 is an enlarged cross sectional view

taken on line 3—3 of Fig. 2, looking in the direction indicated by the arrows, and

Fig. 4 is a perspective view of a fragment 60 of the sharpener showing a means for detachably securing the sharpening member or sheet to the supporting member or body of the sharpener at the corners thereof.

Like numerals of reference refer to corresponding parts throughout the different 65 views of the drawing. The reference numeral 5 designates one of the hands, usually the left hand, of the user of the device, on the palm of which the body or supporting member 6 of the sharpener is mounted and

held in position thereon by means of a strap 70 or piece of tape 7 located transversely with and at about the middle of the member 6, and said strap has its ends secured to the edges of the member 6 by being stitched

75 thereon, or in any other suitable way. The member 6 may be made of any suitable size, form and material, but by preference is substantially rectangular in shape and of sufficient size to almost entirely cover the palm

80 and fingers of the hand. In order to render the body or supporting member 6 of sufficient rigidity or stiffness to maintain its position closely against the hand and yet to allow it to conform to the contour there-

85 of said member is preferably made of pliable material, such as leather, leatherette or the like, and may have its inner surface lined with rep-cloth 8, or some suitable rough material. At each of its corners the body or

90 supporting member 6 is provided on its inner surface with a socket 9 to engage button heads 10, which are secured on the inner surface of the sharpening member 11, and near each of its corners. The sockets 9 and

95 the button heads 10 provide fasteners for detachably connecting the sharpening member 11 to the body or supporting member at the corners thereof, and said fasteners may be of the ordinary and well-known glove

100 fastener type. Near one of its ends the member 6 is provided with a gromet 12, by means of which it can be hung up, when not in use, on a nail or other projection. The

sharpening member or sheet is of substantially 105 the same size and shape as the supporting member or body 6, and is by preference made of linen huck, which as is well-known has a cellular or rough surface. By

110 preference the sharpening member 11 is formed of two plies 12 and 13 (see Fig. 3 of the drawing), that is, said member is made

of a single piece folded back upon itself at its lower edge, and has its end edges and its upper edges secured together by stitches 14. By this arrangement the lower edge of 5 the sharpening member 11, which will be subjected to more or less friction from the razor blades and the hand 15 in which the same are held in the operation of sharpening them, will be prevented from raveling. As 10 shown in Fig. 1 of the drawing, when the parts have been assembled as above set forth and the sharpener is mounted on the palm of one hand, the razor blade may be gripped between the thumb and fore finger of the other 15 hand and placed slantingly on the sharpening member 11 near one end thereof, when it can be slid along the surface of the sharpening member to near the other end of the same, when, by proper manipulation, the 20 blade 16 can be turned so as to bring its opposite surface in contact with the sharpening member and moved back thereon to near the opposite end thereof. This operation may be repeated as often as is deemed 25 necessary, and when one edge of the blade has been sufficiently sharpened, the other edge thereof can be presented in a similar manner to the sharpening member, and the movement above described repeated. By 30 this operation it is apparent that the device may be held in substantially a flat plane, or, if desired, an inward curvature can be given to the device by bending the fingers of the hand on which it is mounted slightly 35 inwardly. By this close fitting arrangement of the parts of the sharpener to the hand on which it is mounted, it is manifest that the edges of the blades will be acted on by the sharpening material, which is flexible, 40 in such a manner as to quickly, thoroughly and uniformly sharpen its edges. The body or supporting member 6 is by preference of greater thickness and rigidity than the sharpening member 11, for the purpose of 45 holding the latter in such a way as to prevent it wrinkling when the supporting hand is curved, and also for the purpose of providing a continuous surface against which the blades may act in their movements over 50 the same. The edges of the body or supporting member 6 may be bordered with a suitable binding 17 to add attractiveness thereto, as well as to hold the lining 8, when the same is employed, in position thereon.

As before stated, this lining is of rep-cloth 55 or roughened material, and will thereby prevent the sharpening material creeping or sliding on the supporting body between the fasteners, for it is obvious that as the sharpening member is made of linen huck or similar material the roughened surface and the lining will engage each other sufficiently to prevent independent movement thereof in the movement of the blades over the sharpening member. 60

65

After the device has been used, it is evident that it can be readily removed from the hand and folded into compact form, or, if desired, can be suspended by means of the gromet on a nail or other suitable projection. 70

Having thus fully described my invention what I claim as new and desire to secure by Letters Patent is—

1. A sharpener for razor blades, consisting of a supporting member having means to fasten it on a hand and to sustain it on the palm thereof, a sharpening member mounted on the supporting member, said members having near their corners co-acting fastening means detachably securing them together. 75

2. A sharpener for razor blades, consisting of a flexible supporting member having means to fasten it on a hand and to sustain it on the palm thereof, and a flexible sharpening member detachably mounted on the supporting member. 85

3. A sharpener for razor blades, consisting of a flexible supporting member having its inner surface roughened, a strap secured at its ends to said member and extended across the outer surface thereof at about its middle, and a sharpening member mounted on the inner face of the supporting member and consisting of a sheet of fabric. 90

4. A sharpener for razor blades, consisting of a flexible supporting member, a strap secured at its ends to said member and extended across the outer surface thereof at about its middle, and a sharpening member detachably mounted on the inner face of the supporting member and consisting of a sheet of fabric, the said supporting member being of greater thickness and possessing greater rigidity than the sharpening member. 95 100 105

EDWARD MARSH.
